GLASS BUILDING BLOCK

Nathaniel C. Dryden, Poughkeepsie, N. Y.

Application April 26, 1946, Serial No. 665,150

2 Claims. (Cl. 72—36)

1

This invention has to do with a glass building block. It combines the qualities of structural strength, durability, insulation against transfer of heat and sound, avoidance of condensation, relatively low density, surface protection and decorativeness. In consequence, the block provides a complete cross section of wall which, after installation, needs no outside surface treatment for either decoration or protection; and it may be so made as to need no inside surface treatment after installation.

Blocks of rectangular shape made according to this invention are easily and quickly set in place, and when suitably bonded at the joints make up the main part of the walls. Similarly made blocks of appropriate shapes, similarly set in place, provide the corners, the frames for doors and windows and the junction with roof members. The same basic idea of block construction admits of use for all of these shapes. A building made of these blocks can be constructed in a short time since the individual blocks can be moved and put in place by hand, and yet are of relatively large size, and many of the conventional operations requiring separate skills and individual time-consuming work are eliminated.

In the annexed sheet of drawings which illustrate the invention,

Figure 1 is a perspective view of the block of rectangular shape used for walls;

Figure 2 is a vertical section through the block;

Figure 3 shows, in plan, a corner block;

Figure 4 is a plan view showing a window or door frame in relation to the blocks bordering in at the sides;

Figure 5 is an elevation showing the shape of the blocks and their assembly at the top of a door or window frame.

The block is an integral unit having component bodies of glass of different sorts fused or otherwise bonded together. These component bodies are arranged like layers on edge, each extending from end to end and from top to bottom of the block. At the center is a body 10 of solid glass. On each side of it is a body 11, 12 of cellular glass, sometimes known as foam glass. At the outside of the block is a thinner body or veneer of solid glass, 13, covering the foam glass and forming a decorative surface. Preferably, but not necessarily, there is a veneer 14 of solid glass at the inside also.

Each block has a V-shaped rib 15 running lengthwise on its under face, preferably in the center part 10, and a corresponding groove 16 in

2

its upper face. The rib rests in the groove in the block beneath it and thus the blocks are located properly in relation to each other to form a plumb wall.

5 The veneer 13, which forms a part of the outside wall of the building, can be molded to resemble another kind of building, for example, the surface of a brick or stone building or a shingled or clapboard surface, and the glass can be colored accordingly. The simulation of brickwork is shown in the drawings. In like manner, that part of the outer veneer of a block which is to form a part of the border of a window or door may be shaped and colored to simulate conventional or other architectural treatment. The inside veneer 14 can be given any color and surface effect, smooth or roughened, that is considered appropriate for the wall of a room. Certain blocks used in a building may have the inner veneer in the form of a glass mirror. No plaster, paint or paper is necessary when an inside veneer is included. If the inside veneer 14 is omitted, the surface presented by the foam glass component 11 may be covered or not as desired.

10 25 The dimensions and relative thickness of the component bodies are matters of design for the particular use. In general the veneer is less thick than the inner components, 10, 11, 12, and the outside veneer 13 is thicker than the inside veneer 14. Likewise, the composition of the glass for the different component bodies is open to variation and adaptation to particular needs. The different component bodies of glass may contain non-glass material, and reference to the 30 block as being of glass is not intended to exclude the use of other compatible components for special purposes, the basic characteristics being still those imparted by the fact of using glass.

35 For the corners of the building, there is a similarly made L-shaped block in which all of the strata turn the corner as shown in Figure 3. The blocks 20, 21 bordering the side of a door or window have a recess 22 at one end extending from top to bottom and located preferably in the 40 central body of solid glass. The blocks 23, 24 bordering the top of a door, or the top or bottom of a window, have a similar recess 25 (see Fig. 2) in their border surface, which is the top or bottom surface of the block as the case may be, but 45 these recesses 25 do not extend the full length of the blocks in as much as these blocks 23, 24 extend back into the wall for support and only partly overlie (or underlie) the door or window opening. For example, the recess 25 in a top 50 block need extend only far enough to overlie the

recess 22 in the blocks bordering the opening at the side. The door frame or window frame 28 fits into the channel provided by these complementary recesses in adjoining blocks bordering the opening. The frame is set in the channel as the side blocks are being put in place, and the top blocks are set in place after the frame is in place. Any suitable sealing agency may be used between the frame and the wall of this channel.

In the preferred way of making this glass block, different masses of glass are brought together while still sufficiently molten to fuse at the interfaces and form a strong bond, thus yielding the integral block. This may be done variously. For example, the block is made in a mold having demountable walls and partitions which form compartments corresponding to the five layer-like bodies described above. The mold walls corresponding to the inside and outside face of the block have whatever conformation is to be given to those faces, as for example the simulation of an outside brick wall. The different masses of glass in molten condition, colored where desired, are charged into the respective compartments, and when the glass is still molten enough to fuse at the interfaces the partitions are withdrawn. When the whole is solidified, the walls of the mold are removed. The aeration of the two foam glass masses 11, 12 can be done in the mold. Annealing or other operations are carried out as with any glass block.

If desired, passageways can be formed through each block by placing suitable cores in the mold. Being aligned when the blocks are assembled in a building these passageways serve, for example, as conduits for wiring or to contain pipes. In similar manner, outlets from these passageways can be formed in the mold and if not used can be blocked off. In any program of standardized building units, such access opening need be

formed only in the particular blocks which are to be located where access is needed. The fact that these blocks are cast from molten material give a wide choice as to shape, interior cavities to save weight, and surface configuration, which makes it possible to adapt the blocks to building needs, both structural and decorative.

Having regard to the doctrine of equivalents, I particularly point out and distinctly claim in the following the improvement and combination which I claim as my invention and discovery:

- 10 1. A glass building block comprising a central body of solid glass extending to the ends and to the top and bottom of the block, a mass of foam glass on each side of that body and a veneer of solid glass covering the side of one foam glass component and forming an outside wall surface, all of said components being united in an integral whole.
- 15 20 2. A glass building block according to claim 1 and having a veneer covering the side of the other foam glass component and forming an inside wall surface.

25 NATHANIEL C. DRYDEN.
